UNITED STATES PATENT OFFICE.

BERNARD SAMELSON, OF SENECA FALLS, NEW YORK, ASSIGNOR TO GOULDS MANUFACTURING COMPANY, OF SENECA FALLS, NEW YORK, A CORPORATION OF NEW YORK.

CENTRIFUGAL PUMP.

Application filed April 11, 1924. Serial No. 705,768.

To all whom it may concern:

Be it known that I, BERNARD SAMELSON, a citizen of the United States, residing at Seneca Falls, in the county of Seneca and 5 State of New York, have invented certain new and useful Improvements in Centrifugal Pumps, of which the following is a full, clear, and exact description, such as will enable others skilled in the art to which it applies 10 and use the same.

This invention relates to a pump and aims to provide an improved device of this character, particularly adapted for use in connection with relatively thick or viscous 15 fluids, or fluids containing foreign matter.

It is an object of the present invention to provide a pump which will efficiently perform the purpose for which it is intended and which will also be economically 20 and readily manufactured and assembled.

A further object is to be predicated to the construction of a device of the character stated, particularly adapted for use in connection with fluids having the characteristics 25 afore-mentioned, which device will be of such construction that danger of the pump becoming clogged will be reduced to a minimum.

A still further object is that of furnishing 30 a pump which is preferably of the centrifugal type, and in which, by means of the improved construction afforded by the present invention, any choking action in the impeller channels is reduced to a minimum.

Other objects of the invention will in part be obvious and will in part appear hereinafter.

The invention accordingly comprises the 40 features of construction, combinations of elements, and arrangement of parts, which will be exemplified in the construction hereinafter set forth and the scope of the application of which will be indicated in the claims.

For a fuller understanding of the nature and objects of the invention reference should be had to the following detailed description taken in connection with the 50 accompanying drawing, in which:

Figure 1 is a vertical section through a centrifugal pump of the double suction type and shows a construction within the scope of the present invention;

Fig. 2 is a side view of an impeller of the

"open type" such as is used in the construction depicted in Fig. 1;

Fig. 3 is a transverse sectional view taken along lines 3—3 and in the directions of arrows indicated in Fig. 2; 60

Fig. 4 is a view similar to Fig. 2, but showing an impeller of the "closed type;"

Fig. 5 is a transverse sectional view taken along the lines 5—5 and in the direction of the arrows indicated in Fig. 4; 65

Figs. 6 and 7 are somewhat diagrammatic outside diameter developments of the impeller shown in Figs. 2 and 4 respectively, and

Fig. 8 shows diagrams of the relative 70 area of different sections of the impeller channel.

It will be noted in the foregoing drawings, that the invention has been shown as embodied in centrifugal pumps of the 75 double suction type. It is here to be understood, however, that the invention may be employed to advantage, in certain instances, in connection with different types of centrifugal pumps; and in fact lends itself to use 80 in pumps of numerous different types.

Referring specifically to the drawings, it 85 will be noted that 10 denotes generally a centrifugal pump casing of the horizontal type, which is provided with an inlet passage or chamber 11 adapted to deliver the fluid to be pumped, along the shaft 12 to both sides of an impeller 14, to be described hereinafter. As shown in Fig. 1, the casing is also provided with a discharge passage or chamber 13 encircling the impeller 90 for receiving the fluid as it is delivered thereby and an impeller chamber 15 is located between the inlet passage and the discharge passage through which the shaft 95 12 extends.

In mounting this shaft some leakage preventing means such as, for example, stuffing boxes may be utilized, which are provided with water-seal rings adapted to encircle 100 the shaft. Now referring to the impeller it will be noted that the same includes a body 14 constructed with a view to reducing to a minimum the choking or clogging which takes place particularly at the entrance or intake of the impeller channels, when thick or viscous fluids or liquids carrying foreign substances are being pumped. In order to accomplish such a reduction in clogging, the 105 cross sectional area of the channels at the 110

vicinity of their intake entrances are increased to a maximum extent preferably without varying the shape or position of the impeller blades, which latter are formed according to certain rules so as to attain efficiency in intake and discharge and may ordinarily not be altered without decreasing the efficiency of the pump. Accordingly in forming the impeller 14, the blades 18 are in the present instance disposed in staggered relation and on opposite sides of the web 21 carried by the hub 20, so as to form a plurality of staggered channels 19 each extending from one of a pair of intake chambers 19' to the discharge passage 13. By thus locating the channels it will be readily understood that any channel may be extended between the adjacent channels provided in the opposite side of the impeller; and, consequently, throughout the greater portion of their length these channels may be made equal in depth to the width or thickness of the impeller, less the thickness of the web. In the present instance, therefore, the depth of the channels at a point adjacent the intake ports is considerably greater than the depth of the chambers 19' or the depth of the channels at the point of intake from said chambers; and, since the impeller, in the present instance, is narrower adjacent its periphery than adjacent the hub 20, the channels, as will be observed from Figs. 1, 3 and 5, attain their greatest depth at a point just beyond their intake ports. Since the thickness of the web is small as compared with the width of the impeller, it may be said that the channels are substantially equal in depth to the width or thickness of the impeller. The channels of the impeller under consideration are of this type, their depth being increased at a point adjacent the intake to a depth substantially equal to the width of the impeller, thus providing the maximum space for the passage of a thick fluid at those points where the blades begin to act on the fluid, so that the likelihood of the occurrence of any choking is greatly reduced. It will also be observed that the channels in the present construction attain their greatest depth at a point between the intake and outlet ports, but adjacent the intake port, where clogging is most likely to occur.

The relative depth of different parts of an intake chamber 19' and a channel 19 may be observed in Fig. 8, which shows sections along the lines A—B, A—C, A—D and A—E of Fig. 2. By such construction a maximum cross sectional area of the channels at any desired point may be obtained without distorting the blades which are designed in accordance with accepted rules and practices.

In order to provide proper balance of the impeller on the shaft, the center lines of

the blades and therefore of the channels may be evenly spaced. It will also be observed that in the present exemplification an equal number of blades are provided on each side of the impeller. The channels on each side receive the fluid to be pumped from opposite directions, but they all deliver into a common discharge passage 13, which may encircle the impeller.

The mounting of the impeller on the shaft 75 21 may be accomplished in any well-known manner, such as for example providing sleeves 16 having threaded engagement with the shaft to prevent longitudinal movement and a key 17 to hold the impeller against angular movement.

The impeller shown in Figs. 2 and 3 is of the open type, that is, the channels are defined by walls on three sides. In such cases the casing 10 is conveniently provided with fixed side plates 22 between which the impeller turns. As it will be observed these side plates cooperate to close the channels and in addition give a wiping action which causes the fluid to swirl thereby effecting the dislodgement of any particles that adhere to the surface of the impeller.

The second form of impeller shown in Figs. 4, 5 and 7 is the same as that shown in Figs. 2 and 3 with the exception that shroud plates 23 are carried by the blades 18, thus converting the open channels into closed channels. In such case, the side plates 22 may be dispensed with and wearing rings 24 may be substituted therefor in order to prevent leakage. In other details the construction of this closed impeller shown in Figs. 4 and 5 corresponds to the enclosed type shown in Figs. 2 and 3, and it will be readily understood that the action of the same will be virtually identical.

In the operation of a pump of this type the fluid is directed into the impeller, or piston from both ends through the inlet passage 11 of the casing or cylinder 10. The speed of flow of the fluid as it enters near the center of the impeller is in the present instance slow and tends to result in a clogging or plugging of the impeller channels. However, by increasing the depth of the channels as described above this clogging or plugging as the fluid is drawn into the impeller is reduced to a minimum. Accordingly when the impeller as viewed in Fig. 2 revolves counter-clock-wise, the fluid is forced evenly and efficiently through the channels 19 under the action of the blades 18. All the channels 19 deliver into the common discharge passage 13, and thus pressure is developed for forcing the fluid through the delivery pipes to the desired destination.

Since certain changes may be made in the above construction and different embodiments of the invention could be made without departing from the scope thereof, it is

intended that all matter contained in the above description or shown in the accompanying drawing shall be interpreted as illustrative and not in a limiting sense.

5 It is also to be understood that the following claims are intended to cover all of the generic and specific features of the invention herein described, and all statements of the scope of the invention which, as a 10 matter of language, might be said to fall therebetween.

I claim:

1. In a double suction centrifugal pump, an impeller including a hub and web extending radially from the hub to provide a pair of intake chambers in opposite side faces of said impeller, said web being distorted at a distance from the hub to form a plurality of blades and to provide a plurality of 20 similar channels defined by said blades and communicating alternately with one and with the other of said chambers, said channels being disposed in staggered relationship.

25 2. In a double suction centrifugal pump, an impeller including a hub and a web extending radially of the hub to provide a pair of intake chambers in opposite side faces of said impeller, said web being distorted at a 30 distance from the hub to form a plurality of blades and side wall members, said blades and said members cooperating to enclose a plurality of similar channels disposed in staggered relationship and communicating alternately with one and with the other of 35 said chambers.

3. In a pump, a rotary impeller member including a hub, a web extending radially of said hub and being axially distorted at 40 a distance therefrom to provide a pair of circular intake chambers of substantially equal depth and a plurality of staggered channels, alternate ones of said channels communicating respectively with opposite 45 chambers, and each of said channels having at a point adjacent its respective chamber a depth greater than the depth of said chamber, and means to impel fluid through said chamber.

50 4. In a pump, a rotary impeller member including a hub, a web extending radially of said hub and being axially distorted at a distance therefrom to provide a pair of circular intake chambers of substantially equal 55 depth and a plurality of staggered channels, alternate ones of said channels communicating respectively with opposite chambers, and each of said channels having at a point adjacent its respective chamber a depth substantially twice the depth of said chamber, and means to impel fluid through said chamber.

5. A double suction centrifugal pump comprising a casing, an impeller fixed 65 against other than rotative movement with-

in said casing and including a plurality of blades for impelling fluid through staggered channels between said blades, said channels varying in depth and attaining their greatest depth substantially at those points whereat said blades become effective upon the fluid in said channels.

6. A double suction centrifugal pump comprising a casing, an impeller fixed against other than rotative movement within 70 said casing and including a plurality of blades for impelling fluid through staggered channels between said blades, said channels varying in depth and attaining a depth substantially equal to the width of the impeller 75 at those points whereat the blades become effective.

7. A centrifugal pump including casing and impeller members, said latter members being formed with intake and outlet ports 80 and a channel connecting said ports, the depth of said channel being substantially equal to one-half of the width of the impeller at the intake port, but substantially equal to the full width of the impeller 85 throughout the greater portion of the length of said channel.

8. A double suction centrifugal pump, including a casing, an impeller member mounted within said casing and fixed 90 against other than rotative movement, said impeller member including a plurality of blades adapted to impel fluid through staggered channels between said blades, said channels varying in depth and attaining 95 their greatest depth substantially at those points whereat said blades become operative upon the fluid in said channels, the center lines of said blades and the center lines of said channels being alternately and evenly spaced angularly about the impeller.

9. A double suction centrifugal pump, including casing and impeller members, said latter member being formed with a plurality 100 of intake and outlet ports and with a plurality of staggered channels for the passage of fluid between said ports, each of said channels increasing rapidly in depth from its respective intake port and having a depth substantially equal to the width of the impeller throughout the greater portion of its length.

10. A double suction centrifugal pump impeller to be mounted within a pump casing solely for rotative movement therein and being formed to provide a plurality of staggered channels for the passage of fluid, and means to impel fluid through said channels at different speeds throughout different portions thereof, the depth of each of said channels reaching their greatest extent substantially at that point where the speed of the fluid impelled therethrough is the least.

11. A centrifugal pump impeller to be mounted within a pump casing solely for 110

rotative movement therein and being formed with a plurality of channels for the passage of a fluid and including means for impelling the fluid through said channels, and
5 means for maintaining a substantially constant flow of said fluid towards the intake ends of said channels, said channels extending radially of the body of the impeller and having a relatively great depth adja-
10 cent said intake ends.

12. A centrifugal impeller to be mounted in a casing solely for rotative movement and including a plurality of blades defining a plurality of staggered channels, the center 15 lines of said blades and the center lines of said channels being alternately and evenly spaced angularly about the impeller.

13. A pump including a casing, an impeller mounted solely for rotative movement 20 within said casing and being provided with

staggered channels for the passage of liquid, said impeller causing a movement of said liquid at different speeds throughout different portions of said channels, and said pump channels having their greatest depth at the 25 point where the speed of the liquid impelled therethrough is the slowest.

14. A pump including a casing, an impeller mounted solely for rotative movement within said casing, said elements cooperat- 30 ing to form staggered channels connecting intake and outlet ports, said impeller being arranged to force liquid through said channels at speeds varying between said intake and outlet ports, said impeller and said casing being constructed to have the depth of the channels greatest where the speed of the liquid impelled therethrough is least.

In testimony whereof I affix my signature,
BERNARD SAMELSON.
